UNITED STATES PATENT OFFICE.

SAMUEL J. MACMULLAN AND JOHN M. ULMER, OF WILLIAMSPORT, PENNSYLVANIA,
ASSIGNORS TO WILLIAMSPORT RADIATOR COMPANY, OF WILLIAMSPORT, PENNSYLVANIA, A CORPORATION OF PENNSYLVANIA.

WATER-HEATER.

1,232,587.

Specification of Letters Patent.

Patented July 10, 1917.

Application filed December 27, 1916. Serial No. 139,144.

To all whom it may concern:

Be it known that we, SAMUEL J. MACMULLAN and JOHN M. ULMER, both citizens of the United States, residing at Williamsport, in the county of Lycoming and State of Pennsylvania, have invented certain new and useful Improvements in Water-Heaters; and we do hereby declare the following to be a full, clear, and exact description of 10 the invention, such as will enable others skilled in the art to which it appertains to make and use the same.

This invention relates to water heaters of the sectional magazine feed type and has 15 for its object to provide a heater of this character which will be simple in construction, comparatively inexpensive to manufacture and more efficient in action than those heretofore proposed.

20 With these and other objects in view the invention consists in the novel details of construction and combinations of parts more fully hereinafter disclosed and particularly pointed out in the claims.

25 Referring to the accompanying drawings forming a part of this specification in which like numerals designate like parts in all the views—

Figure 1 is a transverse sectional view of 30 a water heater made in accordance with this invention;

Fig. 2 is a partially sectional, partially elevational view taken on the line 2—2 of Fig. 1;

35 Fig. 3 is an end view of the general type of heater illustrated in Figs. 1 and 2 but showing certain slightly modified forms of construction;

Fig. 4 is an end view partly in section of 40 a still further modified form of construction;

Fig. 5 is a detail sectional view showing a construction of slip nipples useful in connection with the form of invention shown 45 in Fig. 4;

Fig. 6 is a detail sectional view showing a plurality of grate bars in their operative position;

Fig. 7 is a view of the parts shown in 50 Fig. 6 showing the said grate bars after they have been tilted;

Fig. 8 is a plan view of a combined water heating and magazine choke element; and

Fig. 9 is a side elevational view of the parts shown in Fig. 8. 55

1 indicates any suitable support for the water heater, but preferably of the channeled form shown, 2 the individual sectional heating members provided with the flue spaces 3, and the hollow legs 4, and the connections 5 with the return manifolds 6, connected with the return pipes 7, all as will be clear from the drawings. 8 represents the hot water pipe leading from the manifold 9 to the individual radiators of the heating system, and said manifold 9 is connected with the individual heating elements 2 as by the plurality of connections 10. Each individual heating unit 2 is provided with the substantially straight inner surface 12 70 bordering the combustion chamber 13 and with the substantially straight surface 14 disposed at an angle to said surface 12 as indicated. Each of said heating units 2 is further provided with the substantially 75 straight surface 15 which is substantially parallel to the outer surface 17 and which borders the magazine space 16. Located inside the magazine space 16 are the supporting means 18 on which rests the manifold 80 9. At or near the lower end of each surface 15 there is provided the projection or solid lug 19 for a purpose now to be described.

In water heaters of the type made the 85 subject of this invention, it is desirable to provide an automatic feed for the coal and to this end the magazine space 16 is restricted at or near its bottom by means of the member 20 which is provided with the annular space 21 for the accommodation of water and with the overhanging lip 22 adapted to rest upon the lugs 19 with which the individual units 2 are provided. The extreme ends 23 of said restricting member 90 20 also rest upon or are supported by the end casings 25 and 26 of the heater, the said casings 25 and 26 being provided with the orifices 27 and 28 respectively through which said ends 23 are adapted to project, as will 95 be clear from Figs. 2, 3 and 4 of the drawings.

Said casings 25 and 26 are also provided with lugs 29 to accommodate the overhanging lips 22 of the member 20, as will be 100 105 clear from Figs. 3 and 4 of the drawings.

Said member 20 is provided with the hot water pipe connections 30 and 31 adapted to afford a circulation through the space 21 and to convey the said hot water to convenient points for use when desired.

The said choking member 20 is also provided with the passage or hole 32 through which coal or fuel 33 may pass by gravity down into the combustion chamber 13.

Located preferably above said restricting passage 32 is the oscillating rod or member 34 provided with the fin or lip 35 adapted to agitate the coal 33 and thus cause its more even distribution in the combustion chamber, as will be presently described. Said oscillating rod 34 extends to the outside of the heater as indicated in Figs. 2, 3 and 4, so that the coal 33 may at all times be conveniently agitated, to insure an even 20 automatic feed thereof.

It will thus be seen that the coal 33 rests between the straight parallel sides 15 of the individual sections, and upon the restricting member 20, so that a portion thereof passes 25 under the action of gravity through the restricting passage 32 and down into the combustion chamber 13. Located in the combustion chamber 13 are the inclined grates 40 supported at their lower ends as upon 30 the lugs 41 and at their upper ends upon the member 42 which may be hollow as shown and also provided with a water space 43 if desired. The individual grate members 44 are conveniently pivoted as on the rods 45, 35 and said members 44 are provided with the extending shanks 46 each connected to the reciprocating rod 47 as by the individual pivots 48. It thus results that by reciprocating the rod 47 each of the individual 40 members 44 will be moved from their full line position shown in Fig. 6 to their full line position shown in Fig. 7, so that the meeting edges such as 49 of one member 44 and 50 of another member 44 will move 45 from their closed position illustrated in Fig. 6 to their open position shown in Fig. 7. In other words when the meeting edges 49 and 50 of the members 44 are in the closed position illustrated in Fig. 6 the ignited coal and ashes are supported upon 50 said members 44. On the other hand, when the rod 47 has been pulled toward the right as seen in Fig. 6, the said meeting edges 49 and 50 have separated so that the ashes may 55 readily fall down into the spaces 52 between the individual members 44 and be caught between the surfaces 53 and 54 of said members 44 all as will be clear from Fig. 7 of the drawings. When now the bar 47 is re- 60 versed or moved toward the left as seen in Fig. 6, the curved surfaces 54 of the individual members 44 will revolve under the ignited coal, resupport the same and permit the ashes to pass down between the surfaces 65 53 and 54 of the said members 44. The re-

ciprocating rods 47 are conveniently led to the outside of the heater and operated by any suitable means as for example the levers 56 see Figs. 2 and 3.

In the form of heater shown in Figs. 1 and 2, the individual sections 2 may be conveniently secured to the manifolds 6 and 9 by the screw threaded connections 5 and 10 respectively, in the form shown in Fig. 3, tie rods such as 60 may be also used to hold the sections 2 and other parts together while in the form shown in Fig. 4, the hollow nipples 61 provided with the opposed tapered cone like surfaces 62 may be employed wherever desired to secure the parts together. Further in the construction illustrated in Fig. 4, the inclined grates are composed of a plurality of stepped sections 401 and 402, the outer or lower edge or end of the grate 401 being stepped in the ledge 65, 85 and the inner or upper edge of the grate 402 being stepped in the ledge 66 carried by the bar 67 as shown. Otherwise the construction of the grates is or may be the same as illustrated in Figs. 1, 2 and 3.

The operation of this improved heater will be clear from the foregoing but may be briefly summarized as follows:

The individual heating sections are conveniently cast in substantially the form shown, and are secured to their corresponding manifolds 6 and 9 and other associated parts by any suitable and well-known means as indicated. The choke member 20 being in place and the stirring rod 34 having its 95 fin 35 extending down through the orifice 32 of said member 20, coal is introduced through any suitable door such as 70, and is permitted to automatically feed down and uniformly distribute itself over the inclined grates such as 40. The fire being lighted the products of combustion pass up through the flues 3, and out through connections not illustrated. The magazine choke member heats to a certain extent, but being water cooled the coal is not so liable to melt and choke the opening 32 as would otherwise be the case. When any choking or caking occurs, however, a few oscillations of the fin 35 serve to restore the automatic feeding of the coal, and its uniform distribution over the inclined grates 40.

In other words, it is an important feature of the invention that inclined grates are associated with a water cooled choke member 120 such as 20 provided with an agitator such as 35, for such a construction insures a more constant automatic feed of the fuel and requires less attention than would otherwise be possible. In addition to this by inclining the fin 35 to the right or left so as to partially close the opening 32, the quantity of coal passing through said opening can be restricted at will, and therefore, a rough regulation of the fire be had at all times. In ad- 125

dition, if it should be desired that the automatic feed of coal be substantially uniform both when the magazine is full and when it is only partially full, the fin 35 may be held 5 in an inclined position in the opening 32 when the magazine is first filled, and later adjusted to a more nearly vertical position as the coal is used up, thus causing a somewhat even feeding pressure to urge the coal 10 through said opening 32. In order that the coal may be evenly distributed over the grates 40, the control lever 76, Fig. 3, may be moved first to one side and then to the other, and finally secured to one of the catch 15 members 77 in the desired position. In addition to this when it is desired to run only one grate, as in the summer time, the fin may be left so inclined as to practically cut off coal from the other grate.

20 It is obvious that those skilled in the art may vary the details of construction as well as the arrangement of parts without departing from the spirit of the invention and therefore it is not desired to limit this invention to the above disclosure except as 25 may be required by the claims.

What is claimed is:—

1. In a water heater the combination of a plurality of heating sections each provided 30 with a plurality of surfaces adapted to form the walls of a fuel magazine and a combustion chamber; means for securing said sections together and forming a magazine space and a space for a combustion chamber; means 35 comprising lugs carried by said sections for supporting a magazine choking member; a magazine choking member carried by said last named means; a fuel agitating means associated with said choking member; and 40 an inclined grate below said choking member, substantially as described.

2. In a water heater the combination of a plurality of water heating sections each comprising surfaces adapted to form portions 45 of the walls of a fuel magazine and of a combustion chamber; means for securing said sections together to form said magazine and combustion chamber; lugs carried by said sections; a magazine choke member 50 provided with a passage for fuel adapted to rest on said lugs; means for passing water through said choke member; and an inclined grate adapted to receive fuel through said passage located below said choke member, 55 substantially as described.

3. In a water heater the combination of a plurality of water heating sections each comprising substantially straight surfaces adapted to form portions of the walls of a fuel magazine and of a combustion chamber; means for securing said sections together to form said magazine and combustion chamber; lugs carried by said sections; a magazine choke member provided with a 60 passage for fuel adapted to rest on said

lugs; an agitating means associated with said passage adapted to facilitate the movement of fuel through said passage; means for passing water through said choke member; and an inclined grate adapted to receive fuel through said passage located below said choke member, substantially as described.

4. In a water heater the combination of a plurality of water heating sections each 70 comprising straight vertical surfaces collectively adapted to form the entire side walls of a fuel magazine and also provided with inclined surfaces collectively adapted to form the side walls of a combustion chamber; means for securing said sections together to form said magazine and combustion chamber; lugs carried by said sections; a magazine choke member provided with a passage for fuel adapted to rest on said 75 lugs; an oscillating member extending into said passage and adapted to facilitate as well as to restrict the passage of a portion of the fuel therethrough at will; means for passing water through said choke member; 80 and an inclined grate adapted to receive fuel through said passage located below said choke member, substantially as described.

5. As a new article of manufacture a heating unit for a water heater comprising a 85 substantially straight surface adapted to form portions of the walls of a fuel magazine; a surface adapted to form a portion of the walls of a combustion chamber; a lug adapted to support a choke feed member 90 joining both of said surfaces; and a water leg extending along said combustion chamber, substantially as described.

6. As a new article of manufacture a heating unit for a water heater comprising a substantially straight surface adapted to form portions of the walls of a fuel magazine; a plurality of substantially straight and angularly disposed surfaces adapted to form a portion of the walls of a combustion chamber; a lug adapted to support a choke feed member 100 joining said magazine and combustion chamber surfaces; a water leg extending along said combustion chamber surfaces; and a plurality of flues above said 105 water leg, substantially as described.

7. In a water heater the combination of a plurality of water heating sections adapted when assembled to form a fuel magazine; a readily removable magazine choke member; 110 lugs carried by said sections for supporting the sides of said member; casings provided with means for supporting the ends of said member; and means for suitably securing said sections, member and casings together, 115 substantially as described.

8. In a water heater the combination of a plurality of water heating sections adapted when assembled to form a fuel magazine and a combustion chamber; a readily re- 120

125

movable magazine choke member located between said magazine and chamber; lugs carried by said sections for supporting the sides of said member; casings provided with means for supporting the ends of said member; fuel agitating means associated with said member; and means for suitably securing said sections, member and casings together, substantially as described.

10 9. In a water heater the combination of a plurality of water heating sections adapted when assembled to form a fuel magazine; a readily removable magazine choke member; lugs carried by said sections for supporting 15 the sides of said member; casings provided with means for supporting the ends of said member; oppositely inclined grates located below said member; and means for suitably securing said sections together, substantially 20 as described.

10. In a water heater the combination of means for forming a fuel magazine; a choke member provided with a passage located at the bottom of said magazine; a combined 25 pivoted depending agitator and restricting member located in said passage; a pair of oppositely inclined grate bars below said

passage; and means for holding said restricting member in any desired position to restrict at will the amount of fuel fed to 30 one of said grate bars, substantially as described.

11. In a water heater the combination of means for forming a fuel magazine comprising a plurality of independent heating 35 sections; a choke member provided with a passage located at the bottom of said magazine; lugs carried by said sections for supporting said member; a combined pivoted depending agitator and restricting member 40 located in said passage; a pair of oppositely inclined grate bars below said passage; and means for holding said restricting member in any desired position to restrict at will the amount of fuel fed to one of said grate bars, 45 substantially as described.

In testimony whereof we affix our signatures, in presence of two witnesses.

SAMUEL J. MACMULLAN.
JOHN M. ULMER.
